UNITED STATES PATENT OFFICE.

EUGENE WIET, OF SAN FRANCISCO, CALIFORNIA.

BEADING-TOOL FOR BOILER-TUBES.

988,054.

Specification of Letters Patent. Patented Mar. 28, 1911.

Application filed June 1, 1910. Serial No. 564,413.

To all whom it may concern:

Be it known that I, EUGENE WIET, a citizen of the United States, residing in the city and county of San Francisco and State of California, have invented new and useful Improvements in Beading-Tools for Boiler-Tubes, of which the following is a specification.

This invention relates to a beading tool and particularly pertains to a tool for expanding and beading the ends of boiler tubes in the end plates or tube sheets of locomotive boilers and the like.

In the ordinary construction of boilers, the ends of the boiler tubes are inserted in holes punched in the tube sheet and are fastened therein by expanding the tube in the perforation and then beading the end of the tube over the face of the tube sheet so as to cover the joint and strengthen the connection. Usually two separate tools are employed in making this connection; one for expanding the tube and the other for forming the bead.

It is the object of this invention to provide a tool by means of which both the expanding and beading functions can be performed in one operation, and by means of which better work can be done in less time than with separate tools.

Another object is to provide a multiple beading tool which is especially applicable for use in repairing imperfect connections between the tubes and tube sheets, in locomotive boilers, and which is so constructed as to expand and bead the end of the tube at the same time, thus insuring a perfectly tight joint.

The invention consists of the parts and the construction and combination of parts, as hereinafter more fully described and claimed, having reference to the accompanying drawings, in which—

Figure 1 is an elevational view of the invention. Fig. 2 is a plan view. Fig. 3 is a vertical section on the line X X Fig. 2. Fig. 4 is a cross-section on the line Y Y Fig. 1.

In the drawings A represents the tubular handle or hollow shank of the tool through which a loose stem or impact tappet member 2 extends. The outer end of the stem 2

is adapted to be inserted in a pneumatic hammer of any suitable type which imparts successive hammering blows to the stem 2 to operate the tool as later described. The inner end of the stem 2 is slightly enlarged at 2' and rests against a metallic disk or anvil 3 loosely mounted in an enlarged head or housing A' formed on and integral with the shank A. The anvil 3 in turn bears against the inner end of a tool-holder 4 also mounted and guided in the enlarged head A'. This tool-holder 4 extends beyond the head A' and is retained therein by means of helical springs 5. The upper and lower ends of each spring 5 are connected to respective eye-members 7—7'; the eyes 7 on the upper ends of the springs 5 being strung on a wire ring 9 which encircles the shank A and rests in a groove in the shoulder formed at the juncture of the shank A with the enlarged head A'. The eyes 7' on the lower ends of the springs 5 are slipped over and hooked on pins or lugs 10 mounted on the tool-holder 4, the lugs 10 being notched on their under side to have a removable hooked engagement with the eyes 7'. The springs 5 are of such tension as to normally retain the tool-holder 4 in its innermost position in the head A' and against the anvil 3 which is interposed between it and the stem or impact member 2; at the same time the tool-holder 4 has a limited lengthwise movement in the head when struck a blow by the stem 2 and anvil 3. The head 4 is provided with a plurality of longitudinally extending radial slots 11, in each of which a beading and expanding member 12 is pivotally mounted; lugs 13 on each side of the upper end of a member 12 resting on shoulders formed in the tool-holder 4 at the upper ends of the slots 11. The members 12 are supported directly against the anvil 3. The lower end of each member 12 is fashioned with an outwardly and backwardly curved wedge surface 14 leading into a groove or recess 15, corresponding to the required shape of the bead to be formed. The surface 14 from the lower point of the member 12 is curved outwardly in such manner as to contact with the inner wall of a boiler tube when the tool is inserted therein; the member 12 being

pressed into slots 11 and against springs 16. The springs 16 are mounted in the slots 11 and tend to push the expanders and bead-
ers 12, so they stand at an angle to the longitudinal axis of the tool with the groove 15 more remote from the axis than the pivotal points 13. The head A' is radially slotted at 17 to permit of movement of the members 12 and is slotted lengthwise at 18 for the reception of the springs 5.

Any number of expanders and bead-
ers 12 may be mounted in the tool-holder 4 as may be found desirable, but I have found by practice that three will accomplish the purpose for which the device is designed satisfactorily as shown. When the parts are assembled, as shown in Fig. 1, the tool-holder 4 is yieldingly held in the head A', so as to have a limited movement lengthwise thereof, and the several bead-
ers 12 are disposed in distended position under the action of their springs 16 with the cam surfaces 14 and beading grooves 15 projected beyond the periphery of the tool-holder.

In operation, assuming a tube to be inserted through a tube sheet, the tool-holder 4 is placed in the open end of the boiler tube with the beading recesses 15 of the members 12 resting upon the end of the tube; the bowed extension 14 being pressed inward and contacting with the inner wall of the tube a distance equal to or a little greater than the thickness of the tube sheet of the boiler. A pneumatic hammer being connected to the stem 2 and set in operation, rapid impulsive blows are delivered on the latter which are imparted through the stem 2 and the anvil 3 to the inner end of the tool-holder 4 and to the upper ends of the beading members 12. The force of each blow causes the members 12 to move lengthwise and outward at the same time, by reason of the angular relation between the point of the delivered force and the point of contact with the tube, thus causing the tube to be expanded by the lateral impact of the curved extensions 14 and beading the end of the tube by the longitudinal impact of the walls of the grooves 15. The beading and expanding of the tube, occasioned simultaneously as it is, insures a thoroughly tight contact or joint being made between the tube and the tube sheet. By turning the tool one-third of a revolution back and forth from one side to the other, by means of the shank or handle A, the entire circumference of the end of the tube will be acted upon by the members 12. The tool-holder 4 is caused to turn with the handle A by reason of the members 12 extending through the slots 17 in the head A', and is caused to return to its innermost position in the head after each blow of the hammer piston by means of the springs 5.

The members 12 may be readily removed

and replaced by disengaging the plates 7' on the lower ends of the springs 5 from the pins 10, whereupon the tool-holder 4 can be lifted out of the head A' and access given to the members 12.

70

One important feature is that no screws or screw parts are employed.

In repairing leaking tube plates in locomotive boilers it has been found that this device will enable a workman to do better and more efficient work than with the single beading tool now generally in use, in considerably less time, and without appreciable injury to the tube plate.

75

The multiple tool principle embodied in this invention insures a uniform standard of beading, especially in repair work, and does not require the skill in operating necessary in doing the work with a single tool.

80

Having thus described my invention, what I claim and desire to secure by Letters Patent is—

85

1. A multiple beading tool, comprising a tool holder and a suitable support therefor, means holding the tool holder to the support while allowing it to yield longitudinally thereof, a series of radially movable bead-
ers mounted in said yieldable holder, and means for imparting a series of blows through the tool holder simultaneously to all the said beaders.

90

2. A beading tool consisting of a head, housing an anvil member and a tappet member bearing on the anvil; a tool-holder yieldingly held in the head, and a series of lengthwise extending, circumferentially disposed, movable beading members on said tool-holder receiving the impact of said anvil.

100

3. A beading tool consisting of a head having a hollow shank, impulse-delivering means housed in said head and shank, a longitudinally yieldable tool-holder in the head, and a beading tool carried by and extending lengthwise of the tool-holder and having a yielding, radial movement.

105

4. The combination of a tool-holder and a beading tool pivoted therein, extending lengthwise thereof and movable radially thereof, said beading tool having its lower end curved outwardly and upwardly and terminating in a beading groove, a head in which said tool-holder and beading tool is loosely insertible, means for yieldingly holding the tool-holder and beading tool in the head, and means by which a succession of hammering impulses may be imparted to the end of the beading tool housed within said head.

110

5. A beading tool comprising a hollow head with a hollow shank, a tool-holder loosely fitting in the head and yieldingly held thereto so as to have a limited lengthwise movement with regard to the head, radially movable, lengthwise extending

120

130

beading tools carried by the tool-holder, an anvil member in the head against which the tool-holder and beading members are supported, and a stem adapted to be connected 5 to a pneumatic hammer or the like, engaging with said anvil.

In testimony whereof I have hereunto set

my hand in the presence of two subscribing witnesses.

EUGENE WIET.
